ABSTRACT: A precast or molded insole for shoes adapted for use with several different heights of high heels comprising a main body, a first fiber board member formed to receive a preformed steel shank bonded to the bottom of the main body and a second fiber board member for nailing purposes bonded to the main body above said first fiber board member, said main body having a forepart shown as paddle-shaped, a shank depression in the first fiber board member extending longitudinally from in the heel area forwardly to about midway of the insole for the reception of a metal shank, and the like, after lasting, the heel portion rearwardly of the shank depression increasing in thickness. The insole is suitably contoured beneath for elimination of the use of a filler. A thin piece of paper product material is bonded to the forward two-thirds of the insole to assist in cementing the turned under portion of the upper or its lining and the outsole to the insole.

INVENTOR:

MOLDED INSOLE

BACKGROUND OF THE INVENTION

1. Field Of The Invention

The present invention relates generally to the shoe art, and more particularly to a novel precast or molded insole affording use thereof with several heights of high heels.

2. Need In The Prior Art

The shoe industry has long needed an insole which can be used with more than one height of high heel without causing the heel to gap at the back. The applicant's novel insole fulfills the long need.

SUMMARY OF THE INVENTION

In brief, the present novel insole includes a main body having bonded to the bottom of the shank and heel portions a fiber board member having a longitudinal formed steel shank receiving recess extending from in the heel area forwardly approximately to the halfway mark of the insole break of the shank, the heel area rearwardly of the recess being of greatest thickness at the back and decreasing forwardly to the rear end of the recess, an integral filler portion on the bottom side of the insole being provided to eliminate the need of filler material. A heel nailing piece and a bottom forepart cementing piece are bonded to the main body.

Objects of the invention are to provide a novel insole which is adapted to be used with several heights of high heels without effecting gaping at the back, which is made to receive a preformed metal shank, and the like, before the sole is attached and just before the heel is attached, which is streamlined to present a neat appearance, which obviates the use of filler, and which otherwise fulfills the objects and advantages sought therefor.

BRIEF DESCRIPTION OF THE DRAWING

FIG. 1 is a top plan view of an insole incorporating the teachings of the present invention;

FIG. 2 is a bottom plan view thereof; and

FIGS. 3, 4, 5, 6, 7 and 8 are vertical cross-sectional views taken on substantially the lines 3-3, 4-4, 5-5, 6-6, 7-7, and 8-8, respectively.

DESCRIPTION OF THE PREFERRED EMBODIMENT

Referring to the drawing more particularly by reference numerals, 10 indicates generally an insole incorporating the principles of the present invention. The insole 10 includes a main body 11 formed with a paddle-type forepart 12 of substantially uniform thickness except for a depending central area 14 adapted to obviate the necessity of bottom filler in the shoe. A fiber board member 15 is bonded to the bottom of the main body 11 and extends from the rear point thereof forwardly a little beyond midpoint, as indicated by the broken line in FIG. 2. An elongated recess 16 is provided in the member 15 which extends from about midway of the heel portion 18 of the main body 11 forwardly to a point substantially midway of the main body 11, the recess 16 extending within the area of the thickened filler portion. The heel portion 18 from a rear point 20 of the recess 16 to a rear point 22 of the heel portion 18 gradually increases in thickness, as is clear from FIGS. 3 and

8. This increase in thickness permits several heights of high heels to be applied to the heel portion 18 without gaping at the rear; that is, in proper treading relation. A steel shank, or the like, can be placed in the recess 16 before an outsole and/or a

5 heel has been applied to the heel portion 18, which permits forming of the shank before insertion into the recess 16, so that it may have the proper curvature for the particular height of heel applied. It is not practical to bend shanks once molded into an insole. A fiber board heel nailing piece 24 and a thin 10 bottom cementing piece 26 of paper, or the like, are bonded to the main body 11, as shown, the latter being illustrated enlarged as to actual thickness to permit cross sectioning, being much thinner than the fiberboard piece 24.

It is manifest that there has been provided an insole which fulfills the objects and advantages sought therefor.

It is to be understood that the foregoing description and the accompanying drawing have been given by way of illustration and example. It is also to be understood that changes in form of the elements, rearrangement of parts, and substitution of 20 equivalent elements, which will be obvious to those skilled in the art, are contemplated as within the scope of the present invention which is limited only by the claims which follow.

What is claimed is:

1. A cast insole formed to permit operative use thereof with 25 high heels of several heights comprising a forepart, an intermediate shank portion, a heel portion of gradually thickened cross section in the longitudinal central area thereof from about its transverse center to the rear thereof, an elongated recess in the bottom for the reception of a preformed shank member correlated as to curvature to the height of the heel to be attached to the insole, a fiberboard member bonded to the bottom of the heel and shank portion thereof, an elongated shank member receiving recess being formed in said member, and a central portion thickened on the bottom interiorly of the sides in the rear part of the forepart and front part of the shank portion, said elongated recess extending into this thickened bottom central portion.

2. The insole of claim 1 and including a thin paperlike member covering the bottom of the forepart adapted to aid in 40 cementing said insole in and to a shoe structure.

3. The insole of claim 2 in which the forepart is paddle-shaped permitting use thereof for a predetermined range of widths.

4. The insole of claim 2 and including a nailing piece in the 45 upper surface of the heel portion bonded thereto.

5. The insole of claim 1 and including a nailing piece in the upper surface of the heel portion bonded thereto.

6. The insole of claim 1 in which the forepart is of enlarged 50 paddle-shape permitting required trimming and use thereof for a predetermined range of widths.

7. A cast insole formed to permit operative use thereof with high heels of several heights comprising a forepart, an intermediate shank portion, a heel portion of gradually thickening cross section in the longitudinal central area thereof from about its transverse center to the rear thereof, an elongated recess in the bottom for the reception of a preformed shank member correlated as to curvature to the height of the heel to be attached to the insole, a fiberboard member bonded to the bottom of the heel and shank portion thereof, an elongated shank member receiving recess being formed in said member, and a nailing piece in the upper surface of the heel portion 55 bonded thereto.
